US00D750506S

(12) **United States Design Patent**
Ericksen et al.(10) **Patent No.:** **US D750,506 S**
(45) **Date of Patent:** **** Mar. 1, 2016**(54) **TIMER**

(71) Applicant: **Orbit Irrigation Products, Inc.**, North Salt Lake, UT (US)

(72) Inventors: **Kent C. Ericksen**, Centerville, UT (US); **Karl L. Connolly**, Bountiful, UT (US); **Jeffrey C. Thurgood**, Severance, CO (US)

(73) Assignee: **Orbit Irrigation Products, Inc.**, North Salt Lake, UT (US)

(**) Term: **15 Years**

(21) Appl. No.: **29/546,843**

(22) Filed: **Nov. 25, 2015**

Related U.S. Application Data

(60) Continuation of application No. 29/532,141, filed on Jul. 1, 2015, which is a continuation of application No. 29/500,449, filed on Aug. 25, 2014, now Pat. No. Des. 736,104, which is a division of application No. 29/450,680, filed on Mar. 20, 2013, now Pat. No. Des. 713,271.

(57) **CLAIM**

The ornamental design for a timer, as shown and described.

DESCRIPTION

FIG. 1 is an elevated perspective view of a timer according to our new design; and,

FIG. 2 is a front view of the timer shown in FIG. 1. The structural features depicted by broken lines have been shown for the purpose of illustrating portions of the timer that form no part of the claimed design.

1 Claim, 2 Drawing Sheets
